UNITED STATES PATENT OFFICE.

RICHARD MARX, OF PHILADELPHIA, PENNSYLVANIA.

DISHWASHING MACHINE.

Application filed May 7, 1921. Serial No. 427,557.

One object of my invention is to provide a relatively simple and effective machine for quickly and thoroughly washing dishes and which shall be particularly characterized by 5 the provision of novel means for forcibly delivering water to such dishes during the washing operation.

Another object of the invention is to provide a novel form of bucket or container 10 for successively receiving bodies of water and delivering the same to or over the dishes to be washed in such manner that foreign substances adhering to them shall quickly and certainly be removed, the invention 15 more especially contemplating a construction whereby the rotation of the bucket or container causes a stream of water to be continuously and forcibly delivered upon the dishes practically from the time it emerges 20 from the mass of water at the bottom of the machine until the time it again moves into said water.

The invention further contemplates a novel means for supporting the dishes to be 25 washed relatively to a rotary bucket which discharges thereon a continuous stream of water, whereby the insertion and removal of said dishes is materially facilitated.

I further desire to provide novel means 30 whereby the operation of a dish washing machine will be prevented while the cover thereof is raised or open.

These objects and other advantageous ends I attain as hereinafter set forth, reference 35 being had to the accompanying drawings, in which,

Fig. 1 is an end elevation of a dish washing machine constructed in accordance with my invention;

40 Fig. 2 is a vertical section of the machine shown in Fig. 1, taken on the line 2—2 of said figure;

Fig. 3 is a fragmentary vertical section on the line 3—3, Fig. 2; and

45 Fig. 4 is a fragmentary perspective view of one of the buckets.

In the above drawings, 1—1 represents a suitable frame on which is supported a tank or container 2, usually made of sheet metal. 50 The lower portion of this container is preferably semi-cylindrical in form and its upper portion of rectangular section, open at the top and having hinged to one edge a cover 3. Within the container is mounted a tray 55 or basket 4 for the reception of dishes to

be washed and one of the end members 5 of said tray is rotatably mounted upon a trunnion 6 fixed to and projecting inwardly from one of the flat side walls of the container. The second end member 7 of the tray 60 is likewise rotatably mounted upon a spindle 8 which in turn is rotatably carried in a bearing 9 supported by the second of the side walls of said container 2.

The tray preferably consists of an open 65 frame covered with more or less coarse wire netting and its end members 5 and 7 are preferably extended upwardly at its rear side where there is hinged to them a plate or saucer rack 10. This latter is ordinarily 70 supported in a substantially horizontal position by its pivots and the pins 10^a projecting laterally from bars 5^a carried by the frame or body of the tray. Said end members are also connected by a transverse bar 75 11 having projecting pins or hooks 12 designed to receive the handles of cups to be washed. The body of the tray or basket has upwardly projecting and suitably placed sets of rods 13, preferably inclined to the vertical 80 so as to separate and hold in place the larger dishes to be washed.

Rotatably mounted on the trunnion 6 is a spider 14 and a second spider 15 is similarly mounted on but fixed to the spindle 8. These 85 two spiders each consists of a hub and two pairs of oppositely projecting arms designed to support buckets 16 whose construction is illustrated in detail in Figs. 3 and 4. Said buckets each consists of a sheet metal or 90 light cast structure in the form of a flattened, laterally elongated container of a length slightly greater than the length of the dish-containing tray or basket, closed at one laterally extending edge or side and open 95 at the opposite and advancing side.

Each of the buckets is so mounted on its supporting arms that as the latter are rotated within the container 2 it will scoop 100 up and be filled by the water in the bottom of the container under the dish tray. In accordance with my invention each of the buckets or scoops is characterized by having an opening or slot 17 extending laterally for its full length in its inner side and that 105 edge of said opening nearest the closed end or bottom of the bucket is bent outwardly to form a projecting lip 18. The opposite edge 19 of the opening is similarly bent inwardly.

The outer end of the spindle 8 has mounted on it a pulley wheel 20 connected by a belt 21 to a smaller pulley 22, driven through a spindle and worm gearing 23-24 and a small motor 25 suitably carried upon a table or bracket 26 supported by the lower part of the frame 1 below the container 2. Under the lower part of the latter is mounted a suitable heating device which in the case 10 illustrated consists of a pair of burner pipes 26 supplied from a fuel pipe 27 through a controlling valve 28 whereby water in said container may be heated. For drawing off such water when desired, a single outlet pipe 15 29 is provided and this is equipped with a valve 30 controlled by an operating rod 31 vertically slideable on one side of the container 2.

Under conditions of use the dishes to be 20 washed are placed within the tray or basket 4 for which purpose the cover 3 is raised and the rack 10 is swung upwardly into the positions shown in Fig. 3. The larger dishes are preferably placed between the sets 25 of rods 13, the cups are hung on the hooks 12 and after the rack 10 has again been swung to a substantially horizontal position, the saucers are placed in engagement with the rods 13^a thereof. A suitable quantity 30 of water (in a typical case about two gallons) is then placed in the container, the fuel controlling valve 28 is turned on and the gas or other fuel ignited as it escapes from the burner pipes 26. The water in the 35 container is thus heated and, with the quantity noted, is brought to the boiling point in about six minutes. The motor 25 is then started and through the gearing 24-23, pulley 22, belt 21, pulley 20, spindle 8, the spider arms 14 and 15 with the buckets 16 are rotated, in the present case in a counter-clockwise direction. As a consequence the buckets successively 40 dip into and are filled by the water in the bottom of the container 2 and as they move upwardly from their lowest position the water in each of them begins to flow out 45 through the opening 17.

It is particularly to be noted that this 50 opening is placed in the inner side of each bucket about midway between the open and closed ends thereof, so that during the upward movement of the bucket the water 55 flows out of it under the head due to the mass of water between the open end of the bucket and said opening. This water is delivered forcibly toward the dishes in a continuous stream or sheet extending for practically the full width of the container, and 60 the dimensions of the opening and of the bucket are such that this flow is maintained without interruption while the bucket is moving upwardly. As each bucket swings over the dish tray and moves downwardly, 65 the flow of water from its opening 17 con-

tinues without interruption, being delivered from the lower part of the bucket between said opening and its closed end. The lip 18 insures that the water is delivered in a well defined stream from the opening 17, 70 without tending to adhere to and run down the outside surface of the bucket, while the lip 19 insures the delivery of water from the opening 17 while the bucket is moving downwardly. 75

The motor operates the buckets at such a speed that there is thus a continuous flow from each bucket practically from the time it moves out of the body of water in the bottom of the container to the time it re- 80 enters the same and this flow takes the form of an unbroken sheet which is forcibly delivered upon and into all parts of the various dishes carried by the basket 4. Since the water so delivered flows under an appreciable head from within each bucket and also falls through some distance before striking the dishes, the latter are effectually cleaned, all pieces of solid or greasy material being invariably washed off by the 85 forcible abrading action of the water, which action is hastened and further made certain by reason of the fact that the water is practically at boiling temperature.

After the machine has thus been operated 90 for a suitable time, varying from two to four minutes, and depending on the condition of the dishes, the operation of the motor 25 is stopped and by means of the operating rod 31 the valve 30 is opened to allow the 95 water in the container 2 to flow out into a suitable receptacle such as the pail 33. For a short time thereafter the burner 26 is continued in operation so that what 100 small amount of water still remains in the container 2 and on the dishes is vaporized, after which the fuel valve 28 is closed. Said container is now full of steam which 105 effectively sterilizes the dishes and leaves them in a perfectly clean, polished condition. 110 Thereafter the cover 3 may be opened and said dishes removed.

If desired I may control the operation of the motor 25 by means of a switch 34 having two elements of which one is mounted 115 on the body of the container 2, while the other is mounted on the cover 3. The latter through a flexible conductor 35 is connected to a suitable source of current and the former is connected to the motor through 120 a second conductor 36. With this arrangement the movement of the cover 3 to its closed position closes the switch 34 and thus supplies current to the motor 25.

In a typical case above described the 125 motor is operated at such a speed that the buckets 16 make twenty revolutions per minute and their capacity is such that during a two minute operation of the machine 160 gallons of water are delivered to the 130

dishes. Obviously but a single bucket or more than two buckets may be employed without departing from my invention.

One of the essential features and material advantages of my machine resides in the forcible delivery upon the dishes of a succession of streams or sheets of water which flow from the buckets respectively in unbroken streams or masses during all of the time that said buckets are moving above the dish-containing basket. The streams so delivered possess considerable force, since the first part of the flow is due to the head of water in the upper half of the bucket while the latter part of such flow comes from the lower half of the bucket and falls through a relatively great distance. As a consequence not only are the dishes thoroughly washed in a relatively short time but such washing is satisfactorily performed regardless of the material on the dishes or of their position in the basket or tray.

I claim:

1. The combination in a dish washing machine of a container; a relatively fixed structure for supporting dishes therein; with a bucket of flattened form mounted

on a horizontal axis in said container and rotatable about said structure and having one end open to scoop up water from the container as it is rotated, said bucket having a laterally extending slot-like opening formed in its inner side approximately midway between its closed and open ends, and said bucket being provided with an inwardly curved lip projecting inwardly of the bucket along the retreating edge of said opening.

2. The combination in a dish washing machine of a container; a relatively fixed structure for supporting dishes therein; with a bucket of flattened form mounted on a horizontal axis in said container and rotatable about said structure and having one end open to scoop up water from the container as it is rotated, said bucket having a transversely extending slot-like opening formed in its inner side and being provided with lips on the opposite edges of the opening of which that on the advancing edge is curved toward the dish containing structure and that on the retreating edge is curved in the opposite direction.

RICHARD MARX.
